(57) **CLAIM**

The ornamental design for a bag, as shown and described.

DESCRIPTION

FIG. 1 is a Top, Left and Front perspective view of a bag showing my new design;

FIG. 2 is a Front side view of the bag illustrated in FIG. 1; FIG. 3 is a Rear side view of the bag illustrated in FIG. 1; FIG. 4 is a Top plan view of the bag illustrated in FIG. 1; FIG. 5 is a Bottom plan view of the bag illustrated in FIG. 1;

FIG. 6 is a Left side view of the bag illustrated in FIG. 1; and FIG. 7 is a Right side view of the bag illustrated in FIG. 1. FIG. 8 is a Top, Left and Front perspective view of a second embodiment of the bag;

FIG. 9 is a Front side view of the bag illustrated in FIG. 8; FIG. 10 is a Rear side view of the bag illustrated in FIG. 8; FIG. 11 is a Top plan view of the bag illustrated in FIG. 8; FIG. 12 is a Bottom plan view of the bag illustrated in FIG. 8;

FIG. 13 is a Left side view of the bag illustrated in FIG. 8; and

FIG. 14 is a Right side view of the bag illustrated in FIG. 8. FIG. 15 is a Top, Left and Front perspective view of a third embodiment of the bag;

FIG. 16 is a Front side view of the bag illustrated in FIG. 16; FIG. 17 is a Rear side view of the bag illustrated in FIG. 16; FIG. 18 is a Top plan view of the bag illustrated in FIG. 16; FIG. 19 is a Bottom plan view of the bag illustrated in FIG. 16;

FIG. 20 is a Left side view of the bag illustrated in FIG. 16; and,

FIG. 21 is a Right side view of the bag illustrated in FIG. 16. The broken lines shown in the drawings are included for the purpose of illustrating portions of the bag and form no part of the claimed design.

1 Claim, 18 Drawing Sheets
